UNITED STATES PATENT OFFICE.

ZAREH H. KEVORKIAN, OF FAIRFIELD, ALABAMA.

BY-PRODUCT COKE OVEN.

Application filed July 7, 1919. Serial No. 309,192.

To all whom it may concern:

Be it known that I, ZAREH H. KEVORKIAN, a citizen of the United States of America, residing at Fairfield, in the county of Jefferson and State of Alabama, have invented certain new and useful Improvements in By-Product Coke Ovens, of which the following is a specification.

This invention relates to an improved recuperative oven or retort for use in carbonizing material, and is adapted for single or group construction, preferably the latter for economy of construction and operation. This improved by-product charcoal oven is primarily designed for the destructive distillation of wood of any kind for the recovery of all of the by-products found and for the production of charcoal. However it can be very readily adapted for carbonization of other materials.

My invention has for its object to provide such a by-product charcoal oven having its constituent parts designed and organized so that in a marked degree simplicity, compactness, practicability of operation and economy in normal cost of construction and operation are obtained.

My invention is peculiarly designed to avoid use of regulation, of heat in the combustion chamber and to provide a spaced lining to obtain a more uniform treatment of the entire product than would be obtained if the wood were allowed to contact with the highly heated oven walls.

A further important object is the placing of the oven so that it will be surrounded by recuperating agencies, the radiant heat from which is taken up by air supplied to the combustion chamber surrounding the oven and is thus efficiently utilized.

My invention is also peculiarly designed for utilizing the less valuable part of the charcoal in the oven as the means for heating the oven, it being found that the by-product gas obtained from the charcoal oven is inadequate to heat it.

My process and the preferred apparatus for carrying it into effect are illustrated in a preferred embodiment only in the accompanying drawings which form a part of this specification, and in which:—

Figs. 1 and 2, respectively, show a sectional elevation and a plan of the oven.

Fig. 3 shows a sectional plan.

Similar reference numerals refer to similar parts throughout the drawings.

As illustrated in Figs. 1 and 3, cylinders 2 and 3 of suitable size and material are placed within each other and supported by a metal base 4, which in turn is supported by the concrete structure 1. The cylinders 2 and 3, being placed concentric, afford a uniform annular space 5. Cylinder 3 has a series of holes 62 at its bottom, the function of which will be described later. A row 66 of refractory brick 6 is placed in checker form allowing proper recesses between the bricks for the circulating air necessary for the combustion of fuel within space 5. 7 in Fig. 1 is a metal ring fitting in and covering the annular space 5 between cylinders 2 and 3 at the top, said ring having holes 8. 9 is a hopper supported by the ring 7 and fitted to be turned on the top of cylinder 2 by a handle 10. Said hopper 9 is provided with holes 11 corresponding to holes 8 in ring 7. The ring 9 is made to turn by the application of power at handle 10. 12 in Figs. 1 and 3 is a metal ring of suitable material fitting in the bottom of the space 5 formed between 2 and 3 and resting on and supported by the base 4. The ring 12 has at one side a boss projecting through a slot made in the bottom edge of the cylinder 2 to receive a lever 13 projecting through the checkerwork brick 6 and the concrete structure 1. The said ring is also provided with suitable holes 14 and fitted to turn on 4 when power is applied at lever 13. The metal base 4 supports 2, 5 and 12 and is supported by concrete structure 1, said base having holes 15 corresponding to holes in 12 but shorter in length. A pipe 16 leads from the upper part of the space 5 into a flue 17 formed in the concrete structure 1 95 and connecting to a suitable stack 18 (Fig. 2). 19 is a circular damper fitting in pipe 16 and made to rotate freely by means of a lever 20. 21 is a hole of a suitable size cut in the concrete structure and opening 100 into checkerwork 6. A car 22 of suitable size and construction and having a spout 23 is supported by wheels 24 and adapted to travel on rails 25. A pipe 26 of suitable size is embedded in the concrete structure 1 105 and provided with branches 27 and 28, said pipe 26 being closed at each end. The base has formed therein an annular ring projecting upwardly in the bell at the base of the cylinder 3 and at its bottom having an annular groove containing pliable and uncombustible packing ring material 35 for the

cover 29 that seals the bottom opening of 3 completely air tight. 31 is a lever with a pin 32 supporting the cover 29 loosely. 33 is a fulcrum pin for said lever fitting into 6 bearings 34, Fig. 3, supported by the concrete structure 1. The lever 31 is made fork shape at the fulcrum point to provide accurate setting of cover 29 on its seat 35. 36 is a link connected to the power arm of the 10 lever 31 by means of a suitable pin 37. 40 is a rod having suitable threads on one end and the other end forked to connect to the link 36 by means of a pin 41. A suitable stand 42 is supported on a suitable floor and 15 has a hand wheel 43 threaded to receive the screw end of rod 40 thus providing means for operating the lever 31 by the turning of a hand wheel 43. Condensers 44 consist of heads 44^a, a top vapor section 44^b, 20 a lower vapor section 44^c, and an intermediate tube section 44^d. The lower vapor section 44^c is provided with branches 45 (Fig. 3), to the T 46, a branch of which is connected to the elbow 28 which includes a 25 valve 47. The top vapor section 44^b is provided with branches 48 (Fig. 2) receiving the pipe 49 which has a suitable opening on the side in the center. 50 is a sleeve of suitable construction clamped onto pipe 49, 30 said sleeve having a hole to receive a bent pipe 51 and coincide with hole in pipe 49 and said sleeve being made to turn freely on said pipe 49. 52 is a lid of suitable material and construction 35 resting on a seat 53 of pliable and non-combustible material placed in a ring groove made in the seat 54. The bent pipe 51 fits into the top of the lid 52 and affords a free opening from the chamber 55 through pipes 40 51, 49 and 48 into the top vapor chamber 44^b. A cylinder 59 smaller than and fitting into cylinder 3 is made of woven wire of suitable size forming an inner circular chamber 55. The condenser 56 is composed of top and 45 bottom vapor heads 56^a and the intermediate tube chamber 56^b. The top vapor head has a connection to an exhauster of suitable design and capacity through a pipe 57^a. The bottom vapor head has a connection leading 50 to branch 27 on the pipe 26. A chute 57, formed in the concrete structure 1, leads into a conveyor 58, said conveyor leading into an elevator of suitable size and construction not shown. 55 A cold water pipe line 60 is provided to furnish the necessary water to the condensers 44 and 56, and a water outlet line 61 is provided to convey the warm water after leaving said condensers. 63 is a pipe 60 furnishing fuel vapor through a pipe 64 into the chamber 55 in conjunction with charcoal fuel. Said fuel vapors being obtained from the uncondensable vapors derived from wood carbonized in the chamber 55. 65 Having described the construction and

the constituent parts of the oven in detail, I will now describe its operation.

Wood is brought in and cut to suitable lengths and elevated into a bin of suitable capacity by means of a suitable elevator 70 conveyor.

The fuel used to produce the necessary heat for carbonization is charcoal replenished by the uncondensed vapors obtained from distillation of wood. Said fuel charcoal is also elevated into a suitable bin by means of a suitable elevator conveyor. Car 22 is run under the bin containing wood and receives a charge sufficient to fill the chamber 55. Lid 52 swinging on pipe 49 is 80 lifted and the chute 25 on the car 22 is placed in the dot and dash line position shown. In this position car 22 is made to discharge its contents completely filling space 55 after which chute 23 is lifted into the position shown and lid 52 swung back into position closing chamber 55 air tight. Car 22 receives a charge of charcoal from the charcoal bin above referred to and conveys said charge into the hopper gate 9 90 through chute 23 adjusted. From hopper 9 charcoal is discharged into space 5 through openings 11 and 8, the hopper then is moved to a position where holes 8 are totally closed. Having also closed holes 15 95 by moving 12 by the handle 13 the charcoal charge is ignited in chamber 5, receiving the necessary air through the hole 21, checkerwork 6 and holes 62 by the action of draft caused by stack 18 through flue 17 and pipe 16, regulated by damper 19 by means of handle 20 and creates an intense heat in the chamber 5. To this fuel is added the vapor fuel entering through pipes 63 and 100 64 into said chamber. The heat created in chamber 5 heats cylinder walls 3 and 2, the heat passing through wall 3 is utilized to carbonize the charge in 55 and the heat passing through wall 2 superheats the air passing through checkerwork 6 before entering into the chamber 5 through holes 62. 105

The purpose of the woven wire cylinder 59 is to prevent the wood charge in 55 from coming into direct contact with cylinder wall 3. The heat passing through cylinder wall 3 into chamber 55 drives out the by-products contained in the wood in the form of vapor, said vapors passing through pipes 51, 49 and 48 into the top vapor sections 44^b of the condensers 44. 110 Thence the vapors flow through 44^b, 44^c into 44^d, and thence through pipe 46 and elbow 28 into pipe 26, and thence through condensers 56 to the pipe 57. 115

The flow of vapors formed in chamber 55 through their path described is aided an exhauster (not shown) connected to 57, said pipe receiving all gases that are not condensable at ordinary temperatures. Said gases are then placed in a holder (not 120 125 130

shown) to be used as fuel in the ovens, being let into combustion chamber 5 through pipes 63 and 64.

After all the vapors and gases are driven off from wood charged in 55 and charcoal only remains, cover 52 is swung open thus closing hole in pipe 49 to prevent entrance of air into condensers 44, then bottom cover 29 is opened by means of hand wheel 43, 10 rod 40, actuating link 36 and lever 31.

The contents of 55 are then discharged into chute 57 and led into metal conveyor 58 to be quenched and elevated into the charcoal bin referred to above. A fraction of said charcoal made is used for fuel in the ovens, the balance being loaded for shipment. Handle 13, which can be operated by hand or arranged to be operated by a machine, is to shake the ashes formed 20 on the chute 57 from which it is swept into belt 58 to be conveyed into an ash bin as a by-product. The sweeping of 57 clear of ashes being done just before opening bottom 29.

25 The condensates collected in pipe 26 which contains all liquid products derived from wood, carbonized in chamber 55, are then pumped into a still of suitable design where they are fractionized and the various products recovered separately.

What I claim as new and desire to secure by Letters Patent, is:—

1. A by-product oven of the character described comprising an inner retort for the material to be treated, a fuel burning furnace surrounding said retort, movable top and bottom closures for said retort, and an annular grate for said furnace.

2. A by-product oven of the character described comprising an inner retort for the material to be treated, a fuel burning furnace surrounding said retort, movable top and bottom closures for said retort, a movable ported closure for the top of said furnace, and an annular grate for its bottom.

3. A by-product oven of the character described comprising an inner retort for the material to be treated, a fuel burning furnace surrounding said retort, and movable feed and grate elements at the top and bottom of said furnace.

4. In a by-product oven of the character described, an inner closed retort, a cylindrical wall forming a combustion chamber surrounding the retort, an air heating recuperative checkerwork surrounding said cylindrical wall, there being hot air and fuel admission openings in said combustion chamber, outlet flues for the gases from said retort and chamber, and means to evacuate said retort and chamber.

5. In a by-product oven of the character described, an inner closed retort, a cylindrical wall forming a combustion chamber sur-

rounding the retort, an air heating recuperative checkerwork heated by the combustion chamber, there being hot air and fuel admission openings in said chamber, outlet flues for the gases from said retort and chamber, and means to evacuate said retort and chamber.

6. In a by-product charcoal oven, a closed retort, movable top and bottom closures therefor, an annular wall forming a combustion chamber about said retort having air inlet and ash discharge openings at its base and fuel admission and gas outlet openings at its top, checkerwork surrounding and spaced from the outer wall of said combustion chamber, and means to cause the air supply for said chamber to flow through said checkerwork.

7. In a by-product oven of the character described, an outer marginal wall, a brick checkerwork within said wall, a tubular furnace wall surrounded by and spaced from the checkerwork and having communication therewith near its base, a tubular retort wall surrounded by and spaced from said furnace wall, and means for carrying off the gases from said chambers.

8. In a by-product oven of the character described, an outer marginal wall, a brick checkerwork within said wall, a tubular furnace wall surrounded by and spaced from the checkerwork and having communication therewith near its base, a second tubular retort wall surrounded by and spaced from said furnace wall, and means for carrying off the gases from said chambers.

9. In a by-product oven of the character described, an outer marginal wall, a brick checkerwork within said wall, a tubular furnace wall surrounded by and spaced from the checkerwork and having communication therewith near its base, said wall projecting above and below the checkerwork, a second tubular retort wall surrounded by and spaced from said furnace wall, means for charging of materials from above into the chambers within and without said inner element, and means to carry off the gases from said chambers.

10. In a by-product oven of the character described, an outer marginal wall, a brick checkerwork within said wall, a tubular furnace wall surrounded by and spaced from the checkerwork and having communication therewith near its base, a second tubular retort wall surrounded by and spaced from said furnace wall and having its top and bottom ends exposed, means to charge from above materials into the chambers within

and without said inner element, and means to carry off the gases from said chambers.

11. In a by-product oven, an outer tubular jacket, a brick checkerwork lining in said jacket, a metallic base supported by the jacket, two concentric spaced metal cylinders supported by said base and forming between them an annular furnace which is surrounded by said checkerwork, there being an air inlet port near the top of the checkerwork and air inlet ports to admit the air pre-heated in said checkerwork into said furnace near its base, independent bottom closures for the furnace and for the retort formed in the inner cylinder, and fuel doors and gas ejection pipes for said furnace and retort.
12. In a by-product charcoal oven, a verti-

cal closed retort, an ash chute below said retort, a charcoal furnace surrounding the retort, and independent doors to evacuate 20 said retort and furnace into said chute.

13. In a by-product charcoal oven, an annular furnace comprising a concrete base and jacket, a retort mounted in the annular furnace, a chamber for the collection of 25 condensates in the furnace base, and means to collect and conduct the vapors from the retort to said chamber.

In testimony whereof I affix my signature.

ZAREH H. KEVORKIAN.
